SHOE SOLE ATTACHING PRESS

Francesco Paul Lioy, Passaic Park, N. J., assignor
to Rex Shoe Machine Co. Inc., New York, N. Y.,
a corporation of New York

Application September 16, 1932, Serial No. 633,437

4 Claims. (Cl. 12—33)

This invention relates to a shoe sole attaching press for use in repair of shoes, wherein the soles are usually attached by means of adhesive solution, cement or the like.

5 An important object of the invention is to provide a simple and efficient press which may be held in the lap of an operator so that the pressing operation may be practiced in a convenient and efficient manner.

10 Another object of the invention is to provide a shoe sole attaching press that is comparatively inexpensive to manufacture, so that it may be cheaply sold to the ordinary shoemaker for practice in his trade.

15 With these and other objects in view the invention consists in the novel details of construction, combination and arrangement of parts as hereinafter more specifically described, and illustrated in the accompanying drawing, wherein is

20 shown an embodiment of the invention, but it is understood that changes, variations and modifications can be resorted to which fall within the scope of the claims hereunto appended.

25 In the drawing wherein like reference characters denote corresponding parts throughout the several views;

Figure 1 is a side elevational view of a shoe sole attaching press in accordance with this invention and with a shoe mounted therein.

30 Figure 2 is a vertical cross sectional view taken on the line 2—2 of Figure 1, looking toward the right and

35 Figure 3 is a vertical cross sectional view taken on the line 3—3 of Figure 1, looking toward the right.

Referring to the drawing in detail, P designates the press, S a shoe mounted therein, and L the usual form of last mounted in the shoe.

The press comprises a base, portion 3, in the form of a frame open at its rear end, and formed of a bottom 4 and upwardly projecting front and side walls 5 to provide a pocket for receiving a pad of sponge rubber 6, or other suitable elastic cushioning material. The rubber pad is mounted on a sheet of stiffer material, such as leather or the like, 7, which is secured to the bottom of the frame by means of rivets, 8.

Secured to and projecting from opposite sides of the base, at the central portion thereof, is an upright 9. Braces 9^a extend from the upper ends of the uprights 9 to the rear end of the base 3, and braces 9^b extend from the upper ends of the uprights to the base at points near the front end of the latter. The upper ends of the uprights 9 are connected by a threaded bearing 10, for re-

ceiving a threaded pressure rod, 11, having on its upper extremity a handle, 12, and on its lower extremity a ball portion, 13, for engaging in a socket, 14, provided in the top of the shoe last L, at the ball portion of the shoe. The pressure rod 11, and the handle 12, are arranged to provide a clamping device for attaching the sole X to the shoe at the ball portion thereof.

Secured to the fore portion of the base and projecting upward therefrom, is a yoke 15. At the middle of the yoke is a threaded bearing, 16, for receiving a threaded pressure rod, 17, having on its upper extremity a handle 18, and on its lower extremity a ball portion, 19, for engaging in a socket 20, provided in the top of a plate, 21. The plate is provided for holding on its bottom portion a rubber pad, 22, which prevents damage to the toe portion of the shoe when the press is in use.

The ends of the arms of the yoke, 15, are pivotally connected by bolts 23, to the lower ends of the front braces 9^b, so as to permit the yoke to be swung into and out of its operative position when desired. The threaded pressure rod 17, handle 18, and pressure pad 22, are arranged to provide a clamping device for attaching the sole X, to the shoe at the toe portion thereof.

Secured to the rear portion of the base near the lower ends of the rear braces 9^a and formed on the bottom 4, is a threaded bearing 24, for receiving a threaded pressure rod 25, having on its lower extremity a handle 26, and on its upper extremity a ball portion 27, for engaging in a socket 28, provided on the bottom of a plate 29. The plate 29 is arranged to engage the underside of the leather stiffener 7, and press the rubber pad into contact with the sole X, at the shank portion of the shoe.

In practice, to resole a shoe, the shoe and the new outsole to be attached to the shoe are properly treated with a suitable adhesive, and then secured together in their proper relation. The shoe with the last therein, is then inserted into the press and the three pressure-applying devices, namely, the pressure-applying device for the ball portion of the shoe, the pressure-applying device for the toe portion of the shoe, and the oppositely opposed shank pressure-applying device, are then manipulated for securing the sole to the shoe throughout its length. In tightening the pressure-applying devices, the rubber cushion causes the pressure to be distributed over the sole in an even and uniform manner, so that the cement makes every part of the sole fast against the shoe.

In addition to supporting the uprights 9, the rear braces 9^a reinforce the base 3 near the pressure-applying screw 25, and the front braces 9^b reinforce the front end portion of the base and provide means to which the yoke 15 may be conveniently connected. The ball pressure-applying device has a fixed position horizontally with respect to the base 3. The pivotal connection of the yoke 15 with the base 3 permits the toe pressure-applying device to be adjusted forwardly and rearwardly with relation to the ball pressure-applying device, whereby to adapt the press for resoling shoes of different sizes. In adjusting the press for the size of the shoe to be resoled, it is only necessary to adjust the toe pressure-applying device forwardly or rearwardly with relation to the ball pressure-applying device, the shank pressure-applying device automatically assuming, due to its rockable pressure-applying head 29, the required position, that is, a substantially parallel position, with relation to the shank of the shoe. While the shoe is being clamped in the press, the shank pressure-applying device forces the shoe bodily towards the base 3, and the toe and shank pressure-applying devices rock the shoe forwardly about the head 13 of the shank pressure-applying device, to clamp the ball and toe portions of the new sole firmly against the shoe. The ball and shank pressure-applying devices cooperate to clamp the shank portion of the new sole firmly against the shoe. The shoe is connected to the ball pressure-applying device for universal rocking movement with relation thereto, and the heads 21 and 29 of the toe and shank pressure-applying devices are connected to their respective screws for universal rocking movement with relation thereto, to the end that the forces developed during the turning up of the pressure-applying devices may be utilized to clamp the new sole under substantially uniform pressure throughout its entire area against the shoe.

What I claim is:—

1. A shoe sole attaching press, comprising a base, a pressure-applying device carried by and located above the base, a last for the shoe located

between the pressure-applying device and base and pivotally connected between its toe and shank to said device, a pressure-applying device carried by the base and located above the toe of the last, and a pressure-applying device carried by the base below the shank of the last. 80

2. A shoe sole attaching press, comprising a base, a ball pressure-applying device carried by and located above the base, said pressure-applying device having a fixed position horizontally with relation to the base, a toe pressure-applying device located above the base and pivotally connected to the base for adjustment towards and from the ball pressure-applying device to adapt the press for shoes of different sizes, and a shank pressure-applying device carried by the base and having a pressure-applying head rockable upwardly and downwardly to accommodate itself to the shank of shoes of different sizes. 85 90

3. A shoe sole attaching press, comprising a base, a pad on the base, a pressure-applying device carried by the base and located above the pad, a last for the shoe located between the pad and pressure-applying device and having universal rocking connection with the pressure-applying device between its toe and shank, a pressure-applying device carried by the base and having a universally movable head located above the toe of the last, and a pressure-applying device carried by the base and having a universally movable head located below the pad at the shank of the last. 95 100 105

4. A shoe sole attaching press, comprising a base, uprights secured to opposite sides of the base between the ends of the latter, rear braces 110 extending from the upper ends of the uprights to the base, front braces extending from the upper ends of the uprights to the base, a ball pressure-applying device carried by the uprights, a shank pressure-applying device carried by the 115 base adjacent the points where the rear braces are connected to the base, a yoke connected to the front braces and extending upwardly therefrom, and a toe pressure-applying device carried by the yoke. 120 125
